UNITED STATES PATENT OFFICE.

DANIEL F. FERNEY, OF GRAND RAPIDS, MICHIGAN, ASSIGNOR TO GRAND RAPIDS SCHOOL EQUIPMENT CO., OF GRAND RAPIDS, MICHIGAN.

VISE.

1,195,346.

Specification of Letters Patent. Patented Aug. 22, 1916.

Application filed January 14, 1916. Serial No. 72,123.

To all whom it may concern:

Be it known that I, DANIEL F. FERNEY, a citizen of the United States, residing at Grand Rapids, county of Kent, State of Michigan, have invented certain new and useful Improvements in Vises, of which the following is a specification.

This invention relates to improvements in vises.

10 The main objects of this invention are: First, to provide in a vise an improved adjusting mechanism. Second, to provide in a vise an improved adjusting mechanism which is capable of very rapid and easy manipulation. Third, to provide an improved device having these advantages which is comparatively simple and compact in structure and not likely to get out of repair in use.

20 Further objects, and objects relating to structural details, will definitely appear from the detailed description to follow.

I accomplish the objects of my invention by the devices and means described in the 25 following specification.

The invention is clearly defined and pointed out in the claims.

A structure which is a preferred embodiment of my invention is clearly illustrated 30 in the accompanying drawing, forming a part of this specification, in which:

Figure I is a perspective view of a structure embodying the features of my invention. Fig. II is an inverted view thereof with the bottom plate of the frame removed. Fig. III is a vertical longitudinal section on a line corresponding to line 3—3 of Figs. II, IV and V, the screw being shown in full lines. Fig. IV is an enlarged transverse section on a line corresponding to line 4—4 of Figs. II and III. Fig. V is a transverse section on a line corresponding to line 5—5 of Figs. II and III. Fig. VI is a top perspective view of the split nut shifting member. Fig. VII is a perspective view of one of the split nut members. Fig. VIII is a detail transverse section on a line corresponding to line 8—8 of Fig. III.

In the drawing, similar reference characters refer to similar parts throughout the several views, and the sectional views are taken looking in the direction of the little arrows at the ends of the section lines.

Referring to the drawing, the frame 1 is

adapted to be bolted on the under side of 55 a bench or support to support the vise jaw 2 in operative relation to the edge of the bench or support. The frame is provided with groove-like ways 3 for the slide 4 of the jaw. The adjusting screw 5 is journaled 60 in the jaw at 6 and is provided with a suitable handle 7. The frame is shaped to receive the screw below the jaw slide 4.

A pair of split nut members 8 is provided to coact with the screw, the members 8 being 65 oppositely disposed so that when adjusted to one position they engage the screw so that the jaw is adjusted by the turning of the screw and when adjusted to another position they free the screw so that the jaw 70 slide may be moved freely. These jaw members 8 are provided with bar-like slides 9 disposed transversely of the frame. The side members 10 of the frame are recessed or notched at 11 to receive and support the 75 slides, the slides being arranged side by side so that their ends project through these notches as shown in Figs. I, II, and IV. The nut sections are offset on their slides so that they are opposite and when in screw 80 engaging position form substantially a complete nut. The slides 9 are provided with cam lugs 12 which are engaged by the shifting member 13 disposed below the slides 9 and supported for sliding movement longitudinally thereof by the bottom plate 14 of the frame (see Figs. III and IV).

The shifting member 13 is plate-like in form and is provided with oppositely disposed inclined slots 15 which receive the 90 lugs 12 so that when the plate is shifted longitudinally the slides 9 are shifted transversely of the screws to engage and disengage the nut members. The shifting member 13 is provided with a tooth-like lug 16 95 engaging a spiral groove 17 in the actuating member 18. The actuating member 18 is rotatably mounted upon the screw but is supported against longitudinal movement thereon. The actuating member 18 is provided with a friction block 20 bearing on the screw, so that when the screw is rotated the actuating member tends to rotate therewith unless prevented by engagement with stops, the housing or extension 21 on the 100 actuating member, in the structure illustrated, being adapted to engage the jaw slide, thus limiting the rotative movement

of the actuating member. The friction block is pressed against the screw by the spring 22 held in its housing by the pin 23. The movement of the actuating member is such that when the nut members are in disengaging position and the screw is turned in the jaw clamping direction the shifting member is actuated sufficiently to engage the nut members. Owing, however, 10 to the friction connection for the actuating member to the screw continued movement of the screw is permitted to clamp the jaw. The reverse movement of the screw will rotate the actuating member to its opposite 15 position and this acting on the shifting member 13 disengages the nut members permitting free longitudinal adjustment of the screw and with it the vise jaw. The jaw is preferably provided with a sliding dog 24 20 which may be adjusted to project above the surface of the bench as at 25, indicated by dotted lines in Fig. III.

With the parts thus arranged, the vise may be very quickly and easily adjusted to 25 clamp or release work. The structure is strong and durable and at the same time comparatively simple and compact.

I have illustrated and described my improved vise in an embodiment which I have 30 found to be very satisfactory. I have not attempted to illustrate or describe various modifications which I contemplate, as I believe the disclosure made will enable those skilled in the art to which this invention relates to embody or adapt the same as taste 35 or conditions may dictate. I desire, however, to be understood as claiming my improvements specifically in the form illustrated as well as broadly within the scope of 40 the appended claims.

Having thus described my invention, what I claim as new and desire to secure by Letters Patent, is:

1. In a vise, the combination with a supporting frame, of a jaw slidably mounted in said frame, a jaw-adjusting screw rotatably connected to said jaw, a pair of oppositely disposed split-nut members provided with bar-like slides disposed side by side 50 for movement transversely of the screw, said slides having lugs thereon, a plate-like shifting member disposed below said slides for adjustment transversely thereof and having oppositely disposed inclined slots coacting 55 with said lugs on said slides; whereby, when the shifting member is actuated, said nut members are actuated to engage or disengage the screw, said shifting member having a lug thereon, an actuating member rotatably mounted on said screw and having a spiral groove therein coacting with said lug on said shifting member, whereby, when the actuating member is rotated, said shifting member is actuated, a friction block carried 60 by said actuating member and coacting with a

said screw, a spring for said friction block, and stops for limiting the rotative movement of said actuating member on said screw.

2. In a vise, the combination with a supporting frame, of a jaw slidably mounted in 70 said frame, a jaw adjusting screw rotatably connected to said jaw, a pair of oppositely disposed split-nut members provided with bar-like slides disposed side by side for movement transversely of the screw, said slides 75 having lugs thereon, a plate-like shifting member mounted for adjustment transversely of said slides and having oppositely disposed inclined slots coacting with said lugs on said slides, whereby, when the shifting member is actuated, said nut members are actuated to engage or disengage the screw, said shifting member having a lug thereon, an actuating member rotatably mounted on said screw and having frictional 80 connection therewith, said actuating member having a spiral groove therein coacting with said lug on said shifting member, whereby, when the actuating member is rotated said shifting member is actuated, and means for 85 limiting the rotative movement of said actuating member on said screw.

3. In a vise, the combination with a supporting frame, of a jaw slidably mounted in 90 said frame, a jaw adjusting screw rotatably connected to said jaw, a pair of oppositely disposed split-nut members supported for 95 sliding adjustment transversely of said screw and having lugs thereon, a shifting member mounted for adjustment transversely of said 100 split-nut members and having oppositely disposed inclined slots coacting with said lugs thereon, whereby, when the shifting member is actuated said nut members are actuated to engage or disengage the screw, said shifting member having a lug thereon, an actuating member rotatably mounted on said screw and having a spiral groove therein coacting with said lug on 105 said shifting member, whereby, when the actuating member is rotated, said shifting member is actuated, a friction means carried by said actuating member and coacting with said screw, and means for limiting the rotative movement of said actuating member 110 on said screw.

4. In a vise, the combination with a supporting frame, of a jaw slidably mounted in 115 said frame, a jaw-adjusting screw rotatably connected to said jaw, a pair of oppositely disposed split-nut members provided with bar-like slides disposed side by side for movement transversely of the screw, said slides 120 having lugs thereon, a plate-like shifting member mounted for adjustment transversely of said slides and having oppositely disposed inclined slots coacting with said lugs on said slides, whereby, when the shifting member is actuated, said nut members are actuated to engage or disengage the 125

130

screw, an actuating member rotatably mounted on said screw having frictional engagement therewith, said actuating member having operative connection with said actuating member, so that when the actuating member is rotated, said shifting member is actuated, and means for limiting the rotative movement of said actuating member on said screw.

- 10 5. In a vise, the combination with a supporting frame, of a jaw slidably mounted in said frame, a jaw adjusting screw rotatably connected to said jaw, a pair of oppositely disposed split-nut members supported
15 for sliding adjustment transversely of said screw and having lugs thereon, a shifting member mounted for adjustment transversely of said split-nut members and having oppositely disposed inclined slots coacting
20 with said lugs thereon whereby, when the shifting member is actuated, said nut members are actuated to engage or disengage the screw, said shifting member having a lug thereon, and an actuating member rotatably mounted on said screw and having frictional connection therewith, said actuating member having a spiral groove therein coacting with said lug on said shifting member whereby when the actuating member is rotated in opposite directions by said screw said shifting member is reciprocated.
30 6. In a vise, the combination with a supporting frame, of a jaw slidably mounted in said frame, a jaw adjusting screw rotatably connected to said jaw, a pair of oppositely disposed split-nut members supported for sliding adjustment transversely of said screw, and having lugs thereon, a shifting member mounted for adjustment transversely of said split nut members and having oppositely disposed inclined slots coacting with said lugs thereon whereby when the shifting member is actuated said nut members are actuated to engage or disengage the screw, and an actuating member rotatably mounted on said screw and having frictional connection therewith, said actuating member having operative connection with said shifting member so that when the actuating member is rotated in opposite directions by

said screw said shifting member is reciprocated.

7. In a vise, the combination with a supporting frame, of a jaw slidably mounted in said frame, a jaw adjusting screw rotatably connected to said jaw, a pair of oppositely disposed split-nut members supported for sliding adjustment transversely of said screw, a shifting member mounted for adjustment transversely of said split-nut members and having operative connections therewith, whereby, when said shifting member is reciprocated, said nut members are actuated to engage and disengage said screw, said shifting member having a lug thereon, and an actuating member rotatably mounted on said screw and having frictional connection therewith, said actuating member having a spiral groove therein coaxing with said lug on said shifting member; whereby, when the actuating member is rotated in opposite directions by said screw said shifting member is reciprocated. 55 60 65 70

8. In a vise, the combination with a supporting frame, of a jaw slidably mounted in said frame, a jaw adjusting screw rotatably connected to said jaw, a pair of oppositely disposed split-nut members supported for sliding adjustment transversely of said screw, a shifting member mounted for adjustment transversely of said split-nut members and having operative connections therewith, whereby, when said shifting member is reciprocated said nut members are actuated to engage and disengage said screw, and an actuating member rotatably mounted on said screw and having frictional connection therewith, said actuating member having operative connections with said shifting member so that when the actuating member is rotated in opposite directions by said screw said shifting member is reciprocated. 75
